UNITED STATES PATENT OFFICE.

JOHN BENNIGER, OF PHILADELPHIA, PENNSYLVANIA, ASSIGNOR TO ALFRED SCHROEDER, OF PHILADELPHIA, PENNSYLVANIA.

EXERCISING APPARATUS.

Application filed October 13, 1925. Serial No. 62,257.

My invention relates to a new and useful exercising apparatus for exercising the human body, and it relates more particularly to a form of exercising apparatus adapted 5 to be used by repeatedly pulling upon a pair of handles carried by such apparatus, either in the seated or in the standing position.

My invention further relates to a novel exercising apparatus, in which, the force to 10 be exerted by the person exercising may be regulated or adjusted and wherein, such force is visually indicated with each operative stroke of the apparatus.

With the above ends in view, my invention 15 consists of an outer stationary housing mounted upon suitable supports, an inner pendant casing pivotally mounted in said stationary housing having a central shaft, a pair of drums rotatably mounted upon said 20 shaft within said pendant casing, each of said drums having wound about it a suitable rope or cord extending to the exterior of the apparatus, carrying suitable handles and each of said drums also having a brake 25 band surrounding it for the purpose of applying the desired resistance.

My invention further consists of suitable 30 means intermediate said stationary housing and said pendant casing within the same, 35 for adjusting the amount of swinging movement of said inner casing when said ropes are unwound from said drums by the pull exerted upon said handles, thereby regulating the force necessary to pull said handles in unwinding said ropes from the corresponding drums.

My invention further consists of a suitable 40 graduated dial carried by the front of said stationary housing and a suitable pointer, 45 and means intermediate said pointer and said pendant inner casing, whereby said pointer will indicate upon said dial the amount of the swinging movement of inner pendant casing and hence, the force with 50 which said ropes are being unwound.

For the purpose of illustrating my invention, I have shown in the accompanying drawings forms thereof which are at present preferred by me, since they will give in 55 practice satisfactory and reliable results, although it is to be understood that the various instrumentalities of which my invention consists can be variously arranged and organized and that my invention is not limit-

ed to the precise arrangement and organization of these instrumentalities as herein shown and described.

Referring to the drawings:—

Figure 1 represents a side elevation of my 60 novel exercising apparatus, embodying my invention, showing the same mounted upon suitable horizontal planks in the form of a rowing machine.

Figure 2 represents a plan view of the 65 same.

Figure 3 represents a section on line 3—3 of Figure 2.

Figure 4 represents a section on line 4—4 of Figure 2.

Figure 5 represents a front elevation of 70 the indicator dial on a slightly reduced scale.

Figure 6 represents a section on line 6—6 of Figure 3.

Figure 7 represents a rear elevation of my 75 novel exercising apparatus.

Referring to the drawings, in which like reference characters indicate like parts, 1 and 2 designate a pair of parallel wooden planks positioned horizontally and preferably placed upon the floor in the form of a 80 rowing machine or the like, upon which may be mounted my novel apparatus 3 and a pair of suitable rests or suitable braces 4 and 5 respectively, as well as a suitable seat, not shown in the drawings, so that the handles 85 6 and 7 of my novel exercising apparatus may be drawn forward in the direction of the arrow 8, shown in Figure 2, while a person is in the seated position upon such seat with the feet abutting said suitable 90 braces 4 and 5, so as to simulate the operation or exercise of a rowing machine.

While in the particular illustration shown in the drawings my novel exercising apparatus is shown applied, more particularly, to 95 a rowing machine, yet it is not confined to such application alone, as it is possible to mount such apparatus either upon the floor or the wall and exercise therewith in the seated or standing position as may be desirable. The apparatus 3 is composed of an outer stationary housing and support 9, of substantially cylindrical shape, having the curved or cylindrical wall portion 10 and the two side plates 11 and 12 respectively, 105 as well as the front projecting portion 13 having a substantially upright face 14. Each of the side walls 11 and 12 of said sta-

tionary outer housing 9 carries a horizontal side flange 15 by means of which, it is secured and supported by the suitable angle irons 16 which are in turn secured to the 5 horizontal planks 1 and 2 by suitable fastening devices 17.

The inner pendant casing 18 is composed of the substantially cylindrical shell 19 and the two end plates 20 and 21, clamped to the 10 ends thereof by means of the axial bolt 22 passing through said two end plates having the nut 23 threaded onto the free end thereof. The end plates 20 and 21 are provided with overhanging flanges 24, which overhang 15 the circumference of said cylindrical shell, thereby automatically to center said end plates with respect to said shell.

The pendant casing 18 is pivotally supported from the horizontal transverse pivot bolt 25 by means of a pair of lugs 26 formed integral with, or secured to said cylindrical shell 19 thereof, said pivot bolt 25, passing through said lugs 26, as well as the end walls 11 and 12 of said stationary housing 9.

25 Upon the axial bolt 22, there are mounted the two similar rotary members 27 and 28 having the corresponding outer brake drums 29 and 30 and the corresponding inner rope drums 31 and 32, said rope drums having 30 their peripheral edges in close proximity to each other but separated by an appreciable space, as shown at 33.

Within each of the brake drums 29 and 30 there is mounted, and operatively interposed 35 between said brake drums and the inwardly extending sleeves or bosses 34 and 35 formed integral with the end plates 20 and 21 respectively, a pair of corresponding flat coiled spiral springs 36 and 37; the inner and outer ends 38 and 39 respectively of each of said springs, being hooked and secured in corresponding slots 40 and 41 in the sleeves 34 and 35 in the brake drums 29 and 30 respectively. Thus, the coiled springs 36 and 37 40 will tend to revolve the rotary elements 27 and 28 and the corresponding brake drums 29 and 30 and the rope drums 31 and 32 in the direction of the arrow 42, shown particularly in Figures 1, 3 and 4.

45 Upon each of the rope drums 31 and 32 there is wound, in helical formation, a pair of flexible ropes, cables, cords or chains 43 and 44 respectively, having their inner ends 45 and 46 fixed to said rope drums in suitable openings 47 and 48 respectively, having their outer ends passing through suitable corresponding slots or openings 49 in the cylindrical shell 19 of the pendant inner casing 18 in the manner shown particularly in Figure 60 3. Thus, upon drawing forward the handles 6 and 7, in the direction of the arrow 8, which are secured to the outer ends of the ropes 43 and 44 respectively, said ropes 43 and 44 will be unwound from said rope drums 31 and 32, in the direction of the ar-

row 49, thereby revolving the rotary members 27 and 28 as well as the brake drums 29 and 30 against the force of the coiled springs 36 and 37. Also upon releasing the handles 6 and 7, the coiled springs 36 and 37 will 70 revolve the rotary members 27 and 28 in the opposite direction, that is, in the direction of the arrow 42, thereby to rewind the ropes upon their respective rope drums.

In order to retard the unwinding of the 75 ropes 43 and 44 in the direction of the arrow 49, that is, to increase the pulling force necessary upon said handles 6 and 7, in the direction of the arrow 8, to unwind the same, there are provided a corresponding pair of 80 brake bands 50 and 51, substantially encircling the corresponding brake drums 29 and 30 and having their inner ends permanently secured to the upper portion of the inner surface of the cylindrical shell 19 of the inner pendant casing 18, by means of the rivets or other fastening means 52 and having their outer ends looped about the arms 55 and 56 of a yoke member 57 and secured thereto by corresponding rivets or other fastening 90 means 58. The yoke member 57, having the two horizontal arms 55 and 56, is provided with a hollow cylindrical cap portion 59 which fits over a corresponding upright hollow cylindrical projection 60, carried by, or formed integral with, the outer stationary housing 9 of my novel apparatus and rests upon suitable helical compression springs 61 within said hollow cylindrical portion which is operatively interposed between the upper 100 wall 62 of the cap portion 59 of said yoke member 57, and the bottom 63 of said projection 60, in such a manner as yieldably to support said yoke member 57 and hence, 105 yieldably to support the outer ends 53 and 54 of said two brake bands 50 and 51 respectively. Thus, upon exerting a pulling force upon the handles 6 and 7 and hence, upon the ropes 43 and 44, in an attempt to draw the same outwardly and to unwind the same 110 from the corresponding rope drums, the pendant inner casing 18, pivoted at 25 will be swung about said pivot in the direction of the arrow 64, being restrained only by the brake bands 50 and 51 which surround the brake drums 29 and 30 respectively. Since the outer or free ends of the brake bands 50 and 51 are held in a yieldable manner by the spring 61, said bands will be tightened upon the corresponding brake drums with a force 115 proportionate to the amount of deflection of said inner pendant casing 18, in the direction of the arrow 64.

Hence, in order to adjust and regulate the 120 pulling force necessary upon the handles 6 and 7 to unwind the ropes 43 and 44 from the corresponding drums, and to maintain such force constantly, there is provided an adjusting or set screw 65 passing through a suitable loose opening 67 in the outer sta-

tionary housing 9, of my novel apparatus, and having its lower end 66 fixed to the cylindrical shell 19 of the inner pendant casing 18. The adjusting nut wheel 68 is threaded onto the threaded portion of the screw 65 and a suitable helical compression spring 69 is operatively interposed between said wheel 68 and the stationary outer housing 9 in a manner shown particularly in Figures 3 and 10. To lessen or decrease the pulling force upon the handles 6 and 7 required to unwind the ropes 43 and 44, it is merely necessary to lower the adjusting wheel 68, thereby tightening the spring 69 surrounding the screw 65 and thereby limiting the swinging movement of the inner pendant casing 18 about the pivot 25, in the direction of the arrow 64 when a pulling force is exerted upon the ropes 43 and 44. By thus limiting the displacement of said inner pendant casing 18, the braking action of the brake bands 50 and 51 is also limited and hence, an adjustment of the pulling force is thus obtained.

25 In order to indicate visually, at all times, the force with which the handles 6 and 7 are being pulled in the direction of the arrow 8, there is provided upon the front face 14 of the stationary housing 9, a suitable graduated dial 70, over which is adapted to travel the pointer 71 carried by the sleeve 72 which is rotatably mounted in said front wall 14. The flat helical strip 73 is pivotally secured to the cylindrical shell 19 of the inner pendant casing 18, at a point 74. The sleeve 72 is provided with a corresponding slot extending therethrough, adapted to receive a flat helical strip 73 and adapted to be revolved thereby, when said strip is forced therethrough longitudinally. Hence, whenever the inner pendant casing 18 is displaced from its normal position, that is, whenever it is swung about the pivot 25 in the direction of the arrow 64, by the pulling force upon the handles 6 and 7, the pointer 71 will be moved across the dial 70 an amount proportionate to the amount of displacement of the inner pendant casing 18 and hence an amount proportionate to said pulling force, since the braking action of the brake bands 50 and 51, against which said pulling force must act is also proportionate to said displacement or swinging of said inner pendant casing 18 about said pivot 25. Thus, there is maintained in view, at all times, a visual indication of the force with which said handles 6 and 7 are pulled, which force, may be increased or decreased, as mentioned hereinbefore, by raising or lowering the adjusting wheel 68.

60 In order to guide the ropes 43 and 44, during the winding and unwinding of the same around the rope drums 31 and 32, there are provided a corresponding pair of guide arms 75 and 76 pivotally secured to the bifurcated

brackets 77 and 78 respectively by means of the pivot bolts 79 and 80, which brackets 77 and 78, are in turn pivotally secured to said cylindrical shell 19 of the pendant inner casing 18 by means of the horizontal pivot 70 bolts 81 and 82, thereby permitting the pivotal movement of said guide arms 75 and 76 in both vertical and horizontal planes. The brackets 77 and 78 are further provided with the stop projections 83 which abut against the cylindrical shell 19, thereby to limit the movement of said brackets about the pivots 81 and 82. The outer ends of the guide arms 75 and 76 are bifurcated and are provided with idler guide wheels 84 and 85 respectively, pivotally mounted between the bifurcated ends thereof about the pivot pins 86 and 87. The helical tension spring 88 is interposed between suitable hooks 89 and 90 on the arms 75 and 76 respectively, in order to urge said two arms towards each other at all times, thereby more properly to guide said ropes 43 and 44 onto the rope drums 31 and 32 respectively.

25 While in the foregoing description and accompanying drawings reference has been made to the particular application of my apparatus to a rowing machine, parts of which are shown in the drawings, it is to be understood that my novel apparatus may be used in a different manner as well, as for instance, by mounting the same on the wall or floor and by exercising therewith in a seated or standing position.

It will now be apparent that I have devised a novel and useful exercising apparatus which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent is:—

1. In a device of the character stated, a stationary support, a frame pivotally carried thereby, a rotary element rotatably carried by said frame, said rotary element comprising a rope drum and a brake drum, a brake band about said brake drum having one end thereof fixed to said frame and having the other end thereof carried by a suitable support operably positioned with respect to the pivot of said frame.

2. In a device of the character stated, a stationary support, a frame work pivotally carried thereby, a rotary element rotatably mounted in said frame work, said rotary element comprising a rope drum and a brake

drum, a brake band about said brake drum having one end thereof fixed to said frame work and having the other end thereof carried by a suitable support operably positioned with respect to the pivot of said frame, a suitable flexible element wound about said rope drum having one end thereof fixed thereto, and tensioning means intermediate said rotary element and said frame work adapted to revolve said rotary element so as to wind said flexible element upon said rope drum.

3. In a device of the character stated, a stationary support, a frame work pivotally carried thereby, a rotary element rotatably mounted in said frame work, said rotary element having a rope drum and a brake drum, a brake band about said brake drum having one end thereof fixed to said frame work and having the other end thereof carried by a suitable support operably positioned with respect to the pivot of said frame, a suitable flexible element wound about said rope drum having one end thereof fixed thereto, tensioning means intermediate said rotary element and said frame work adapted to revolve said rotary element so as to wind said flexible element upon said rope drum, said flexible element being adapted to displace said frame work about its pivot, in a direction away from said yielding brake band support.

4. In a device of the character stated, a stationary support, a frame pivotally carried thereby, a rotary element rotatably carried by said frame upon an axis substantially parallel to said pivot, said rotary element having a rope drum and a brake drum, a brake band about said brake drum having one end thereof fixed to said frame and having the other end thereof carried by a suitable yielding support operably positioned with respect to the pivot of said frame.

5. In a device of the character stated, a stationary support, a frame work pivotally carried thereby, a rotary element rotatably mounted in said frame work, upon an axis substantially parallel to said pivot, said rotary element having a rope drum and a brake drum, a brake band about said brake drum having one end thereof fixed to said frame work and having the other end thereof carried by a suitable yielding support operably positioned with respect to the pivot of said frame, a suitable flexible element wound about said rope drum, and tensioning means intermediate said rotary element and said frame work adapted to revolve said rotary element so as to wind said flexible element upon said rope drum, said flexible element being adapted to displace said frame work about its pivot, in a direction away from said yielding brake band support.

6. In a device of the character stated, a stationary support, a frame work pivotally carried thereby, a rotary element rotatably mounted in said frame work, upon an axis substantially parallel to said pivot, said rotary element having a rope drum and a brake drum, a brake band about said brake drum having one end thereof fixed to said frame work and having the other end thereof carried by a suitable yielding support operably positioned with respect to the pivot of said frame, a suitable flexible element wound about said rope drum, tensioning means intermediate said rotary element and said frame work adapted to revolve said rotary element so as to wind said flexible element upon said rope drum, said flexible element being adapted to displace said frame work about its pivot, in a direction away from said yielding brake band support.

7. In exercising apparatus of the character stated, a stationary support, a frame mounted thereon and freely movable with respect thereto, between suitable limits, a rotary element rotatably carried by said frame, said rotary element comprising a rope drum and a brake drum, a brake member in operative alignment with said brake drum, suitably supported so that a displacement of said movable frame with respect to said stationary support will urge said brake member into operative engagement with said brake drum, thereby to effect a braking action upon said rotary element.

8. In exercising apparatus of the character stated, a stationary support, a frame mounted thereon and freely movable with respect thereto, between suitable limits, a rotary element rotatably carried by said frame, said rotary element comprising a rope drum and a brake drum, a brake member in operative alignment with said brake drum, suitably supported so that a displacement of said movable frame with respect to said stationary support will urge said brake member into operative engagement with said brake drum, thereby to effect a braking action upon said rotary element, and a suitable flexible element wound about said rope drum having one end thereof fixed thereto and tensioning means intermediate said rotary element and said frame adapted to revolve said rotary element so as to wind said flexible element upon said rope drum, said flexible element being adapted to displace said frame with respect to said stationary support, thereby to urge said brake member.

9. In exercising apparatus of the character stated, a stationary support, a frame mounted thereon and freely movable with respect thereto, between suitable limits, a rotary element rotatably carried by said frame, said rotary element comprising a rope drum and a brake drum, a brake member in operative alignment with said brake drum, suitably supported so that a displacement of said movable frame with respect to said stationary support will urge said brake member into operative engagement with said brake drum, thereby to effect a braking action upon said rotary element, and a suitable flexible element wound about said rope drum having one end thereof fixed thereto and tensioning means intermediate said rotary element and said frame adapted to revolve said rotary element so as to wind said flexible element upon said rope drum, said flexible element being adapted to displace said frame with respect to said stationary support, thereby to urge said brake member.

into operative alignment with said brake drum, while being unwound from said rope drum by pulling the free end thereof, against the force of said tensioning means.

9. In exercising apparatus of the character stated, a stationary support, a frame mounted thereon and freely movable with respect thereto, between suitable limits, a rotary element rotatably carried by said frame, said rotary element comprising a rope drum and a brake drum, a brake member in operative alignment with said brake drum, suitably supported so that a displacement of said movable frame with respect to said stationary support will urge said brake member into operative engagement with said brake drum, thereby to effect a braking action upon said rotary element, and a suitable flexible element wound about said rope drum having one end thereof fixed thereto, tensioning means intermediate said rotary element and said frame adapted to revolve said rotary element so as to wind said flexible element upon said rope drum, said flexible element being adapted to displace said frame with respect to said stationary support, thereby to urge said brake member into operative alignment with said brake drum, while being unwound from said rope drum by pulling the free end thereof, against the force of said tensioning means and adjustable means operatively engaging said frame to limit the displacement thereof with respect to said stationary support, to any desired extent, thereby to limit the braking action of said brake member and hence, to limit the force upon said flexible element required to unwind the same from said rope drum.
10. In exercising apparatus of the character stated, a stationary support, a frame mounted thereon and freely movable with respect thereto, between suitable limits, a rotary element rotatably carried by said frame, said rotary element comprising a rope drum and a brake drum, a brake member in operative alignment with said brake drum, suitably supported so that a displacement of said movable frame with respect to said stationary support will urge said brake member into operative engagement with said brake drum, thereby to effect a braking action upon said rotary element, and a suitable flexible element wound about said rope drum having one end thereof fixed thereto, tensioning means intermediate said rotary element and said frame adapted to revolve said rotary element so as to wind said flexible element upon said rope drum, said flexible element being adapted to displace said frame with respect to said stationary support, thereby to urge said brake member into operative alignment with said brake drum, while being unwound from said rope drum by pulling the free end thereof, against the

force of said tensioning means, adjustable means operatively engaging said frame to limit the displacement thereof with respect to said stationary support, to any desired extent, thereby to limit the braking action of said brake member and hence, to limit the force upon said flexible element required to unwind the same from said rope drum, and means actuated by said movable frame visually to indicate the extent of the displacement thereof from its normal position.

11. In a device of the character stated, a stationary support, a frame work pivotally carried thereby, a rotary element rotatably mounted in said frame work, said rotary element having a rope drum and a brake drum, a brake band about said brake drum having one end thereof fixed to said frame work and having the other end thereof carried by a suitable support, a suitable flexible element wound about said rope drum having one end thereof fixed thereto, tensioning means intermediate said rotary element and said frame work adapted to revolve said rotary element so as to wind said flexible element upon said rope drum, said flexible element being adapted to displace said frame work about its pivot, thereby to tighten said brake band when it is unwound against the force of said tensioning means, adjustable means operatively engaging said frame work to limit the displacement thereof about said pivot to any desired extent, thereby to limit the braking action of said brake band and hence to limit the tensional force upon said flexible element required to unwind the same from said rope drum, and a graduated dial, an indicator adapted to be displaced with respect to said dial and means operatively interposed between said indicator and said frame work adapted to actuate said indicator when said frame work is displaced.

12. In a device of the character stated, a stationary housing, a pendant casing pivotally carried thereby, a pair of similar rotary elements rotatably carried by said pendant casing, each of said rotary elements having a rope drum and a brake drum, a brake band about each of said brake drums having the inner end thereof secured to said pendant casing and having the outer end thereof secured to a resilient support, a pair of flexible elements wound about each of said rope drums and having its inner ends secured thereto and its outer end extending beyond said pendant casing, a spring operatively interposed between each of said rotary element and said pendant casing to revolve said rotary elements so as to wind the flexible elements about the corresponding rope drums, whereby the unreeling of said flexible elements by tensional force upon the free ends thereof, will displace said pendant casing about said pivot and tighten

said brake bands about said brake drums thereby to increase the force necessary to unreel said flexible elements.

13. In a device of the character stated, a stationary housing, a pendant casing pivotally carried thereby, a pair of similar rotary elements rotatably carried by said pendant casing, each of said rotary elements having a rope drum and a brake drum, a brake band about each of said brake drums having the inner end thereof secured to said pendant casing and having the outer end thereof secured to a resilient support, a pair of flexible elements wound about each of said rope drums and having its inner ends secured thereto and its outer end extending beyond said pendant casing, a spring operatively interposed between each of said rotary elements and said pendant casing to revolve said rotary elements so as to wind the flexible elements about the corresponding rope drums, whereby the unreeling of said flexible elements by tensional force upon the free ends thereof, will displace said pendant casing about said pivot and tighten said brake bands about said brake drums thereby to increase the force necessary to unreel said flexible elements and an adjusting screw intermediate said stationary housing and said pendant casing to limit the pivotal movement of said pendant casing and hence, to limit the braking action of said brake bands and thus to limit the tensional force required to unreel said flexible elements.

14. In a device of the character stated, a stationary housing, a pendant casing pivotally carried thereby, a pair of similar rotary elements rotatably carried by said pendant casing, each of said rotary elements having a rope drum and a brake drum, a brake band about each of said brake drums having the inner end thereof secured to said pendant casing and having the outer end thereof secured to a resilient support, a pair of flexible elements wound about each of said rope drum and having its inner ends secured thereto and its outer ends extending beyond said pendant casing, a spring operatively interposed between each of said rotary and said pendant casing to revolve said rotary elements so as to wind the flexible elements about the corresponding rope drums, whereby the unreeling of said flexible elements by tensional force upon the free

ends thereof, will displace said pendant casing about said pivot and tighten said brake bands about said brake drums thereby to increase the force necessary to unreel said flexible means, a spring interposed between said stationary housing and said pendant casing yieldably to limit the pivotal movement of said pendant casing and hence to limit the braking action of said brake bands and thus to limit the tensional force required to unreel said flexible elements, and threaded means to adjust the force of said spring.

15. In a device of the character stated, a pivotally supported pendant casing, a pair of rotary elements rotatably mounted therein, each of said rotary elements having a rope drum and a brake drum, a flexible element wound about each of said rope drums having one end thereof secured to the same, and having a suitable handle secured to the outer end thereof, pivotally mounted guide arms secured to said pendant casing and having anti-friction means adapted to guide said flexible elements, resilient means urging said guide arms towards each other and a spring intermediate each of said rotary elements and said pendant casing adapted to reel said flexible elements onto the corresponding rope drums.

16. In a device of the character stated, a pivotally supported pendant casing, a pair of rotary elements rotatably mounted therein, each of said rotary elements having a rope drum and a brake drum, a flexible element wound about each of said rope drums having one end thereof secured to the same, and having a suitable handle secured to the outer end thereof, pivotally mounted guide arms secured to said pendant casing and having anti-friction means adapted to guide said flexible elements, resilient means urging said guide arms towards each other, a spring intermediate each of said rotary elements and said pendant casing adapted to reel said flexible elements onto the corresponding rope drums, a brake band about each of said brake drums having its inner end secured to said pendant casing and having its outer end secured to a resilient support, and adjustable means operatively engaging said pendant casing to limit the pivotal movement thereof about said pivotal support of said pendant casing.

JOHN BENNIGER.
